W. H. HARRISON

GARMENT HANGER SUPPORTING MECHANISM FOR WARDROBE TRUNKS

Filed Jan. 18, 1924

UNITED STATES PATENT OFFICE.

WADE H. HARRISON, OF PETERSBURG, VIRGINIA.

GARMENT-HANGER-SUPPORTING MECHANISM FOR WARDROBE TRUNKS.

Application filed January 18, 1924. Serial No. 687,053.

To all whom it may concern:

Be it known that I, WADE H. HARRISON, a citizen of the United States, residing at Petersburg, in the county of Dinwiddie and State of Virginia, have invented certain new and useful Improvements in Garment-Hanger-Supporting Mechanism for Wardrobe Trunks, of which the following is a specification.

- 10 This invention has general reference to wardrobe trunks and relates more specifically to a garment hanger supporting mechanism therefor and particularly that type of wardrobe trunk known as the hinged-
 15 ly joined, double section type, the primary object of the invention residing in the provision of such a supporting mechanism wherein the garment hanger supporting bar per se is so mounted as to be swung
 20 within or without the trunk for allowing the clothes to be properly positioned therein or to be extended outwardly from the interior of the trunk when it is desired to use the same.
 25 An additional object of the present invention is to provide such a supporting mechanism wherein the same may be removed as a unit from the trunk and associated with a specific form of bracket element that is to be positioned within a closet whereby the articles of wearing apparel may be readily supported within the closet when the traveler reaches his destination.

An additional object of the present invention resides in the provision of certain means whereby the hanger supporting bar per se, may be swung downwardly at an inclination to its carrying means when the mechanism is positioned within a closet, said bar carrying a series of spaced hooks upon its under-side upon which the clothes hangers are to be engaged, it being obvious from this construction that the garments will be supported in stepped relation so as not to take up too great amount of the space within the closet.

With the above and other objects in view as the nature of the invention will be better understood, the same comprises the novel form, combination and arrangement of parts hereinafter more fully described, shown in the accompanying drawing, and claimed.

In the drawing wherein like reference characters indicate corresponding parts throughout the different views,

Figure 1 is a fragmentary elevational

view of the open side of a trunk section equipped with my novel garment hanger supporting mechanism, said mechanism being shown as extended within the trunk,

60 Figure 2 is a longitudinal sectional view through the extreme upper end of this section of the trunk, for disclosing in top plan, my novel garment hanger supporting mechanism,

65 Figure 3 is a vertical sectional view through the garment hanger supporting mechanism per se, the garment hanger supporting arm member being shown in a horizontal fully extended condition and being also fragmentarily shown by the dotted lines in an inclined position with respect to its carrying member, it being well to herein note that this arm is moved to such a dotted line position when the garment hanger mechanism is removed from the trunk section and positioned within a closet,

70 Figure 4 is a detail sectional view taken substantially upon the line 4—4 of Figure 2, for disclosing a certain part of the present invention that is rigidly attached to the interior of the trunk section and this upon one of the side walls at the front open edge of said trunk section, and

75 Figure 5 is a front elevational view of the garment hanger supporting means removed from the trunk and associated with a particular type of support that is to be rigidly secured within a closet.

80 Now having particular reference to the drawing, 5 designates generally, one of the sections of a well known type of wardrobe trunk with which my improved garment hanger supporting mechanism is to be associated.

85 My invention per se embodies the provision of a relatively long plate 6 that is to be rigidly secured to the interior of the trunk section 5 and this upon the side wall thereof opposite from the side wall that is hingedly connected to the other trunk section not shown. Said plate 6 is flanged upon its opposite edges as at 7 whereby said plate may be rigidly secured through the medium of bolts or other fastening means to the wall of the trunk. The inner face of this plate 6 is longitudinally channeled at 8 for the sliding reception of a bolt 9 of relatively greater length than said plate 6. The inner end of this bolt 9 is formed with an abutment 10 for limiting the outward sliding movement of the bolt within

the slot of the plate 6. The outer end of this bolt is formed with a head 11 that is formed with a vertically arranged opening 12, Figure 1.

5 The position of the plate 6 within the trunk is such as to permit the head 11 of the bolt 9 to position directly at the open side of the trunk section when said bolt is forced to its inward limit of movement.

10 Disposed for swinging movement upon the head 12 is a relatively wide arm 13 that is formed at its end adjacent said head with a head 14 in which is a vertical opening 15 for registration with the opening 12 in the head 11 of said bolt 9 whereby a pivot pin 16 may be extended therethrough so as to form the pivotal connection between the arm and the head 11.

15 From a consideration of Figure 1 it will be noted that the position of the arm supporting means is such as to allow but the necessary room between said supporting elements and the top wall of the trunk section whereby as long as the bolt 9 is maintained in its inward limit of movement, it will be impossible to remove said arm from the means to which it is hingedly attached.

20 For maintaining the bolt 9 in its inward slid position for thereby preventing the detachment of said arm, said bolt is provided adjacent its headed end with an opening 17, Figure 4, that registers with an opening in the plate 6, through which may be engaged a pin 18. This pin 18 is carried by the 25 front end of a spring strip 19 that is rigidly secured at its rear end to the plate 6 it being of course obvious that when said pin is positioned in the manner as shown in Figures 2 and 4 it will be impossible to 30 slide the bolt 9 in a forward direction. Any suitable form of latch element 20 may be employed for preventing the retraction of said pin, said means however, being displaceable for allowing the removal of said 35 pin from the opening in the bolt when it is desired to slide the same outwardly for allowing the garment hanger supporting bar carrying arm to be disassociated from its supporting means.

40 The swinging arm 13 is provided with a relatively wide and elongated opening 21 for purposes presently to be set forth, and upon the inner side of this arm at a point above said opening 21 is a plate 22 of sheet metal. Upon the inner side of this plate 22 is a U-shaped bracket 23 extending across the parallel leg portions of which is a pin 24. The underside of said U-shaped bracket 23 is formed at one end with a horizontal wall 25 while formed at the other end of said bracket is an inclined wall 26 both of which are for purposes presently to be set forth.

45 Pivoted secured to this U-shaped bracket 23 through the medium of the before

50 mentioned pin 24 is a bar 27 that includes a pair of sections 28 and 29 said section 29 being pivoted to the free end of the bar 28 as at 30 and adapted to be swung laterally at right angles to said bar section 28 55 when the carrying arm 13 is swung upon its pivot in a direction toward the trunk section for manifestly allowing said sectional bar 27 to be entirely positioned within the trunk section and this in a manner as 60 clearly shown in Figure 2.

55 The garment hangers, not shown, are to be supported upon the bar section 28 when the device is extended within the trunk, it being nevertheless understood that when the 65 arm 13 is moved outwardly away from the trunk section the bar 29 may be swung to a direction parallel with the bar 28 for allowing the garment hangers to be positioned thereon for obviously allowing the different 70 articles of wearing apparel to be spaced apart so that the same may be readily viewed when it is desired to select certain articles. It is preferable that a desirable 75 form of latch means 31 be provided between the free end of the arm 13 and the adjacent side wall of the trunk section for obviously preventing an outward swinging movement of the arm until such a movement is desired.

80 As long as the garment hanger supporting mechanism is associated with the trunk, the sectional bar is maintained at the end of the pin 24 beneath which is the horizontal wall 25 for manifestly preventing a 85 downward swinging movement of the bar upon the pivot pin. However, after the arm 13 has been removed and the same positioned within a closet through the provision of means hereinafter to be described, the bar 90 27 may be moved over onto the other side the pin 24 after which the same will be allowed to swing downwardly into the dotted line position of Figure 3 until the inner end thereof contacts the inclined wall 95 26 upon the opposite side of said bracket 23. The garment hangers are to be associated with suitable hooks 32 upon the under-side of each of the sections of the bar 27 only when the hanger supporting 100 mechanism is positioned within the closet, it being of course obvious that when this bar 27 is allowed to position in inclined 105 dotted line position of Figure 3, but little space will be taken up within the closet.

110 For allowing the garment hanger supporting bar carrying arm 13 to be properly supported within the closet, I employ in connection therewith, a suitable plate 33 that is to be rigidly secured to one of the walls of the closet or the inner side of the door thereof, said plate carrying upon its back side metal straps 34 that have their upper ends extended forwardly of the plate 115 for providing fingers whereby the arm 120 125 130

may be hooked thereover in a manner as clearly shown in Figure 5.

For preventing a sliding movement of the sectional bar 27 upon the pin 24 of the bracket 23 while the same is resting upon the horizontal wall portion 25 thereof, a suitable form of latch finger 35 is provided, the construction of which is also clearly shown in Figure 5.

10 It will thus be seen that I have provided a highly novel and useful form of garment hanger supporting mechanism, for wardrobe trunks and one wherein the entire number of garments within the trunk may be 15 removed when desired, and wherein the supporting mechanism for the garment hangers may be swung outwardly of the trunk for permitting ready access to the same.

20 I do not wish to be limited to the specific structure shown in the drawing and described in the specification, as in the future practice of the invention minor changes may be made therein without departing from the spirit and scope of the appended claims.

25 Having thus described my invention, what I claim as new and desire to secure by Letters Patent is:—

1. A garment hanger including a plate provided with a channel, a bolt slidably 20 mounted in the channel of the plate and

having an angularly disposed extremity which is normally spaced from the end of the plate to limit the sliding movement of the bolt in relation to the plate, a frame pivoted upon the bolt, a bracket mounted 35 upon the frame at a point between the ends thereof and having an inclined wall section and a horizontally disposed wall section, a bar section pivotally mounted upon the bracket and removable over and engageable 40 on the horizontal and inclined wall sections thereof so that the bar section may be supported in either an inclined position or a horizontally disposed position, and a second 45 bar section pivotally connected with the first bar section and arranged horizontally with relation thereto.

2. A garment hanger including a bracket having an inclined wall section and a horizontally disposed wall section, and a bar section pivotally mounted on the bracket and movable over and engageable on the horizontal and inclined wall sections thereof whereby the bar section may be supported 50 in either an inclined position or a horizontal position.

55 In testimony whereof I affix my signature.

WADE H. HARRISON.
